[57] CLAIM

[21] Appl. No.: 773,946

The ornamental design for a gas transport laser apparatus, as shown and described.

[22] Filed: Mar. 3, 1977

DESCRIPTION

[51] Int. Cl. .... D13—99

FIG. 1 is a perspective view of laser apparatus embodying the invention, the view being taken at the corner of the rear or non-transmitting end of the apparatus;

[52] U.S. Cl. D13/19

FIG. 2 is an enlarged rear end elevation of the laser apparatus of FIG. 1;

[58] Field of Search .... D13/19, 40; 331/94.5 G,

FIG. 3 is an enlarged left side elevation thereof;

331/94.5 E, 94.5 D; 330/4, 4.3

FIG. 4 is an enlarged top plan view thereof;
FIG. 5 is an enlarged right side elevation thereof;
FIG. 6 is an enlarged front elevation thereof, the front being the transmitting end of the apparatus.
